UNITED STATES PATENT OFFICE.

CHRISTIAN W. MEINECKE, OF JERSEY CITY, NEW JERSEY, ASSIGNOR TO MEINECKE & COMPANY, OF NEW YORK, N. Y., A CORPORATION OF NEW JERSEY.

COMBINED WATER BOTTLE AND HEATER FOR FOUNTAIN-SYRINGES.

1,161,401.

Specification of Letters Patent.

Patented Nov. 23, 1915.

Application filed October 31, 1913. Serial No. 798,452.

To all whom it may concern:

- Be it known that I, CHRISTIAN W. MEINECKE, a citizen of the United States, residing at Jersey City, county of Hudson, State of New Jersey, have invented a certain new and useful Improvement in a Combined Water Bottle and Heater for Fountain-Syringes, of which the following is a specification.
- 10 My invention relates to a device which may be used as a water bottle for sick room purposes in the usual way, and also for the purpose of heating liquid as it flows from a fountain syringe.
- 15 My invention will be found of particular service in connection with a fountain syringe when the latter is employed to administer saline solutions according to the drip or "drop by drop" method.
- 20 My invention will be better understood by referring to the accompanying drawings in which—

Figure 1 represents a perspective view of a fountain syringe arranged for the rectal administration of saline solutions by the drip method, my improved heating device being applied thereto; Fig. 2 represents, on a larger scale, a side view, part section, of my heating device proper and shows that portion of the syringe tube through and along which the fluid is heated; Fig. 3 represents an edge view of the structure shown in Fig. 2; and Fig. 4 represents a section, as viewed from above, taken along the line 4—4 of Fig. 1.

In the drawings 1, is a metallic receptacle or irrigator reservoir provided with an internal system of graduations 2, by means of which the fluid contents can at all times be read off. An outlet 3, at the bottom of this receptacle connects to a flexible rubber tube 4 provided with a shut-off valve 5 and a regulator valve 6. A glass bulb 7, having a short section of glass tube 8 sealed in the top thereof, is inserted in the tube 4 just below the regulator valve 6. A short rubber tube 9 connects the bottom of bulb 7 with one upper branch of a Y-shaped glass connector 10, the other upper branch of which 40 opens into an auxiliary tube 10' terminated by a hook-shaped glass tube, which may conveniently overhang the edge of the reservoir 1. The bottom branch of connector 10 opens into a rubber tube 11, the lower extremity of 55 which is connected by means of a connecting

glass 12 to one end of a heating section 13, the other end of section 13 being connected through a second connecting glass 14 to a rectal tube 15.

A metallic water bottle 16 has a metallic tube 17 passing diagonally through it from the upper front left hand portion to the lower rear right hand portion. The inner diameter of this tube is such that it closely embraces without compressing the rubber tube 13 and the ends of the tube are soldered, welded or otherwise suitably fastened to the edges of suitable holes made in the side walls of the water bottle.

The connectors 12 and 14 are located just outside the walls of the water bottle and, when in position, expand the ends of tube 13 sufficiently to prevent this tube from being withdrawn.

Disregarding the water bottle for a moment, the operation of the rest of the apparatus, as is well known, is as follows: The receiver 1 is filled with a suitable saline solution, and shut off valve 5 being opened, the regulator valve 6 is adjusted so as to permit the solution to fall into bulb 7 from the outlet 8 at the desired rate, say *e. g.*, 30 to 60 drops per minute. These drops pass on through tubes 9, 10, 11, etc., and out of the rectal tube 15.

The auxiliary tube 10', the glass end of which is shown hooked over the reservoir, takes care of any gases emitted without danger of the rectal tube being expelled.

In the administration of saline solutions by this method, it is important that the solution itself should reach the rectum at about blood heat. It is usual to attempt to secure this result either by heating the solution before it is put into the receptacle or else by heating it after insertion by placing *e. g.*, an electric lamp in the solution. Or the previously heated solution may have its heat maintained by the use of an electric lamp or some equivalent means.

The above methods of heating, while they provide for the initial heating of the liquid, do not, however, insure that the saline solution shall have the required heat after it has passed through the necessarily somewhat long tube. Obviously a great deal of heat is necessarily lost during this movement of the fluid on account of the relatively large radiating surface of the conveying tube as compared with the amount of fluid which is

flowing. As a matter of fact the average loss between the reservoir outlet nozzle and the rectum is about 40° F.

With my invention the fluid is reheated a sufficient amount at a point in the supply tube as near as possible to the end of the rectal tube. This is accomplished by filling the water bottle 16 with hot water, from which heat is transmitted through the metallic tube 17 and the wall of the rubber tube 13, to the fluid which flows therethrough.

The tube 13 embraced by the water bottle is, during the administration of the saline solution, practically full all the time and since only some 30 to 60 drops per minute are allowed to pass into this tube from the outlet 8, of course, only the same amount of fluid flows from the end of the rectal tube in the same time. It is clear that each individual particle of fluid as it passes through tube 13 remains within the said tube a very considerable length of time and has ample opportunity to acquire heat from the water of the hot water bottle. The water in the water bottle 16 may be renewed from time to time as it cools. By disconnecting connectors 12 and 14 the tube 13 may be removed and the water bottle 16 used in the usual way as an ordinary hot water bottle.

I have shown my improved water bottle as having only one straight tube 17. This tube, however, may be replaced by as many tubes suitably connected together as may be desired and the tube, instead of being straight, may be curved, in either of which cases the length of tubing through which the fluid must pass may be correspondingly

increased and therefore, the time during which the fluid receives heat is also increased.

Any form of water bottle may, of course 40 be used to heat the saline solution, provided it have the tube 17 or an equivalent inserted therein according to the plan above set forth and any such bottle would of course, lie within the scope of my invention. 45

Having described my invention, I claim:

1. A combined water bottle and heater for fountain syringe comprising a metallic receptacle adapted to contain hot water and provided with a metal tube passing therethrough, said tube having its ends open and united with the walls of the receptacle, as and for the purpose described. 50

2. In combination a metallic water bottle having a metal heating tube passing therethrough, said tube having its ends open and united with the walls of the receptacle, a rubber tube passing through said heating tube and means for retaining said rubber tube in place. 60

3. As a new article of manufacture an elongated rectangularly shaped metal water bottle and a metallic heating tube passing diagonally through said bottle from end to end said tube having its ends open and united with the walls of the water bottle, as and for the purpose described. 65

In testimony whereof, I have hereunto set my hand in the presence of two subscribing witnesses.

CHRISTIAN W. MEINECKE.
